CLAIM

(21) Appl. No.: **29/824,839**

The ornamental design for a hand-worn tattoo pen wireless power supply, as shown and described.

(22) Filed: **Jan. 27, 2022**

DESCRIPTION

(51) LOC (14) Cl. **13-02**

FIG. 1 is a top perspective view of the hand-worn tattoo pen wireless power supply showing my new design.

(52) U.S. Cl.

FIG. 2 is a front view of the hand-worn tattoo pen wireless power supply.

(58) **Field of Classification Search**

FIG. 3 is a rear view of the hand-worn tattoo pen wireless power supply.

USPC **D13/110; D24/146**

FIG. 4 is a left side view of the hand-worn tattoo pen wireless power supply.

USPC **D13/101, 102, 103, 107, 108, 110, 118,**

FIG. 5 is a right side view of the hand-worn tattoo pen wireless power supply.

D13/119, 123, 184, 199; D14/251, 253,

FIG. 6 is a top view of the hand-worn tattoo pen wireless power supply.

D14/432, 434; D24/108, 133, 146, 147,

FIG. 7 is a bottom view of the hand-worn tattoo pen wireless power supply; and,

D24/232; D26/39

FIG. 8 is a bottom perspective view of the hand-worn tattoo pen wireless power supply.

CPC .. H02J 7/00; H02J 7/027; H02J 7/0042; H02J

Any shading and cross-hatching are not features of the design but are utilized to illustrate the surface contours of the hand-worn tattoo pen wireless power supply design in the drawings.

7/0045; H02J 7/0047; H02J 7/0048; H02J

The broken lines illustrate portions of the hand-worn tattoo pen wireless power supply that form no part of the claimed design.

7/0063; H02J 7/32; H02J 7/1423; A61M

37/0076; A61M 37/0084; A61M 5/48
